CLAIM

The ornamental design for a box for transporting boards, as shown and described.

DESCRIPTION

FIG. 1 is a perspective view of a box for transporting boards showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is another perspective view of FIG. 1.
The broken lines illustrate portions of box for transporting boards and form no part of the claimed design.
